BEVERAGE DISPENSER FAUCET

Irwin J. Albert, Philadelphia, Pa., assignor to Soda Dispenser Inc., Philadelphia, Pa., a corporation of Pennsylvania

Application September 12, 1956, Serial No. 42,906

Term of patent 14 years

(Cl. D2—3)

The dominant features of the design reside in the parts thereof shown in full line.

I claim:

The ornamental design for a beverage dispenser faucet, substantially as shown and described.
